UNITED STATES PATENT OFFICE

GLADYS R. T. WILLIAMS, OF CLEVELAND, OHIO

ELECTRIC BUTTER CHURN

Application filed December 9, 1931. Serial No. 579,941.

The invention relates to a churn and more especially to an electric butter churn.

The primary object of the invention is the provision of a churn of this character wherein the electric power unit is concealed or housed and the same connected with the churn dasher so as to assure smooth and easy operation thereof for churning purposes.

Another object of the invention is the provision of a churn of this character wherein the construction thereof is an improvement over the subject matter of Letters Patent #1,106,006 dated August 4, 1914, the mechanism being of novel form and assembly.

15 A further object of the invention is the provision of a churn of this character which is extremely simple in construction, thoroughly reliable and efficient in its operation, strong, durable, and inexpensive to manufacture.

20 With these and other objects in view, the invention consists in the features of construction, combination and arrangement of parts as will be hereinafter more fully described in detail, illustrated in the accompanying 25 drawings, which disclose the preferred embodiment of the invention, and pointed out in the claim hereunto appended.

In the accompanying drawings:—

Figure 1 is a side elevation of a churn constructed in accordance with the invention.

Figure 2 is a front view thereof.

Figure 3 is a top plan view.

Figure 4 is a sectional view on the line 4—4 of Figure 1 looking in the direction of the 35 arrows.

Figure 5 is a fragmentary sectional view through one of the bearings of the churn structure.

Figure 6 is a perspective view with the 40 parts of the bearing separated.

Similar reference characters indicate corresponding parts throughout the several views in the drawings.

Referring to the drawings in detail, the 45 churn comprises in its make-up a base 10 mounted by front and rear posts 11 and 12 respectively, there being a pair of front posts and a single rear post, these being spaced apart in their vertical position and the base 50 10 has suitably mounted thereon an electric

motor 13 operated from electric house current or other current supply. Fitted about the motor and the lower portions of the posts is a casing or housing 14 provided at its front and opposite sides with swinging doors 15 so that access may be had to the housing at these points. The doors 15 are supported upon hinges 16 and carry knobs 17 for the manual opening and closing thereof.

The top 18 of the casing 14 constitutes a 60 platform while superposed with respect to the latter is an upper platform 19, the latter formed with the posts 11 and 12 and is disposed horizontally and likewise the platform 18.

65 The churn proper comprises a receptacle 20 removably seated against a bracket 21 on the platform 18 and secured thereto by an arm 22 pivoted at one end to a post 11. The pivoted arm 22 partially surrounds the receptacle 20 and is held in place by a removable pin 23 mounted in said arm and passing through a lug 24 on another post 11. The churn dasher includes a head 25 adapted to reciprocate in the receptacle 20 and a stem 26 secured to 70 said head. The stem 26 is slidably fitted in a cover 27 for the receptacle 20.

75 Mounted in a suitable bearing 28 on the platform 19 spaced forwardly of the rear post 12 and also mounted in the latter is a horizontal driven shaft 29, the mounting of which with the bearing 28 and post 12 each includes a stationary cone 30 and a movable cone 31, the latter being fast to the shaft 29 while working between these cones are anti-friction 80 bearing balls 32.

85 On the rear end of the shaft 29 is a belt pulley 33 and likewise on the drive shaft 34 of the motor 13 is a pulley 35 and about these pulleys is trained an endless belt 36 so that motion from the motor 13 will be transmitted to the shaft 29.

90 The forward end of the shaft 29 carries a crank 37, the pin terminal 38 of which extends through a slot 39 in a horizontal crosshead 95 40, the ends of the latter being slidably fitted to guides at the upper ends of the front posts 11. This crosshead through the medium of rigid arms 41 carries a sleeve 42 centrally located with respect to said head and projected 100

outwardly therefrom, the sleeve being fitted with a coupling rod 43. The coupling rod 43 and dasher stem 26 are detachably connected together by means of a pair of inwardly projecting yieldable latch dogs 44 attached to the coupling rod 43 and adapted to interlock with the upper end of the said dasher stem 26 so that when the shaft 29 rotates reciprocatory movement will be imparted to the said stem 26 for the working of the churn as should be obvious.

In the practical use of the churn power is transmitted from the motor 13 to the shaft 29 through the medium of the belt 36 and the crosshead 40 reciprocates in response to rotary movement of the crank 37. The churn dasher is rigidly secured to the crosshead 40 so as to reciprocate in unison therewith.

The churn proper, that is, the receptacle 20 can be readily removed from the platform 18 by releasing the arm 22 and swinging the same outwardly, while the dasher stem 26 can be readily detached from the coupling rod 43 by disengaging the yieldable latch dog 44 from the upper end of said stem 26.

By the anti-friction mounting of the shaft 29 the same has free motion with minimum friction.

What is claimed is:—

30 A churn of the character described comprising a stationary bracket, a clamping arm pivotally supported and cooperating with the bracket for clamping a receptacle therebetween, uprights at opposite sides of the bracket and having grooves in their upper portions, a crosshead between the uprights and slidably fitted in the grooves therein and having a slot, a projection on the crosshead and extended outwardly therefrom, a dasher reciprocatingly mounted in the receptacle and having a stem, a coupling on the projection for detachable connection with the stem, and a power shaft mounted midway between the uprights and having a crank engaged in the slot in the crosshead.

In testimony whereof I affix my signature.

GLADYS R. T. WILLIAMS.
